UNITED STATES PATENT OFFICE

162,743

VALVE FOR PRESSURE COOKERS

Walter C. Lueneburg, Evanston, Ill., assignor to
Ekco Products Company, Chicago, Ill., a corpora-
tion of Illinois

Application January 8, 1949, Serial No. 122

Term of patent 7 years

(Cl. D44—1)

To all whom it may concern:

Be it known that I, Walter C. Lueneburg, a citizen of the United States, residing at Evanston, county of Cook, State of Illinois, have invented a new, original, and ornamental Design for a Valve for Pressure Cookers, of which the following is a specification, reference being had to the accompanying drawing, forming part thereof.

Fig. 1 is a side elevational view of a valve for pressure cookers, showing my new design.

Fig. 2 is a similar view of the article when turned through an arc of 90 degrees about its upright axis relative to position shown in Fig. 1.

Fig. 3 is a top plan view thereof.

I claim:

The ornamental design for a valve for pressure cookers, as shown.

WALTER C. LUENEBURG.
